UNITED STATES PATENT OFFICE.

BOWIE DASH, OF NEW YORK, N. Y.

DESIGN FOR THE ORNAMENTATION OF PAPER.

SPECIFICATION forming part of Design No. 16,291, dated September 29, 1885.

Application filed July 11, 1885. Term of patent 14 years.

To all whom it may concern:

Be it known that I, BOWIE DASH, a citizen of the United States, residing at New York, in the county and State of New York, have 5 invented and produced a new and original Design for the Ornamentation of Paper, of which the following is a specification.

My invention relates to a new and original design for the ornamentation of paper, fabrics, &c., its distinctive novelty consisting, essentially, in the representation of a solid bed or mass of tea spread over the surface of the paper. The leaves of tea are represented as being rolled or curled up, or partially so, presenting 15 the appearance of the genuine article before being used, and are indiscriminately arranged,

lying upon and overlapping each other, as shown in the accompanying drawing, and conveying the idea to the mind of the observer of having been carelessly spread over the surface of the paper. 20

What I claim as new is—

The design for the ornamentation of paper, &c., herein shown and described, which consists in the representation of a solid bed or 25 mass of tea spread upon the surface of the paper.

BOWIE DASH.
